UNITED STATES PATENT OFFICE.

JAMES CROSSLEY, OF BURY, COUNTY OF LANCASTER, ENGLAND, ASSIGNOR
TO JAMES KENYON, OF SAME PLACE.

PAPER-MAKER'S COTTON DRYING-FELT, PRINTER'S MACHINE-BLANKET, AND OTHER MACHINERY CLOTHS.

SPECIFICATION forming part of Letters Patent No. 313,994, dated March 17, 1885.

Application filed June 1, 1884. (Specimens.) Patented in England October 9, 1880, No. 4,103, and February 23, 1884, No. 3,817.

To all whom it may concern:

Be it known that I, JAMES CROSSLEY, a subject of the Queen of Great Britain and Ireland, residing at Bury, in the county of Lancaster, England, have invented certain new and useful Improvements in Paper-Makers' Cotton Drying-Felts, Printers' Machine-Blankets, and other Machinery Cloths; and I do hereby declare the following to be a full, clear, and exact description of the invention, such as will enable others skilled in the art to which it appertains to make and use the same.

The object of this invention is the manufacture of a cotton drying-felt for covering paper-makers' rollers or cylinders which shall be as even at the joint (where the two ends of the fabric are joined together) as at the other part of the surface, and thus present no obstacle to the paper or pulp in passing over the same; and my invention consists in weaving the parts of which the joining is composed half the thickness of the other part, or opposite sides of the fabric, so that when the two half-thicknesses are laid together one over the other and the warp ends are spliced by quilting or sewing together therewith the two half-thicknesses so laid together, a flush and even joining is obtained, the joint being exactly equal in thickness to the other part of the felt.

30 In producing the fabric I employ an ordinary loom containing twelve heddles.

To start a piece of fabric, I commence to weave with half the number of heddles—say those at the back of the loom, corresponding with what may be termed the "face" of the fabric. This is continued until six inches (more or less) of the fabric have been woven of the half-thickness so produced. I then op-

erate all the heddles, and so produce the full thickness of the material until the required 40 length is produced. I then stop off the other half of the heddles—say those at the front of the loom, corresponding with the face of the fabric—and weave another six inches (more or less) of half-thickness; and in taking the piece 45 from the loom a short length of unwoven warp-threads is left attached at each end of the piece. The half-thickness ends are now laid together and securely united in the act of stitching in the protruding warp-threads, as 50 aforesaid.

In accordance with this invention a joining is effected without tying the warp ends together, and which dispenses with all knots and other projections.

55 It will be apparent that this invention is equally applicable to seaming together the ends of printers' machine-blankets and other endless machinery cloths.

I claim as my invention—
60 An improved endless felt blanket or machinery cloth of uniform thickness, composed of a piece of woven fabric having overlapping ends each of half-thickness, the outer sides of which form continuations of the respective 65 sides of the fabric, while their inner sides come together at mid-thickness of the fabric, and are united by means of the stitched-in warp ends, substantially as herein specified.

66 In testimony whereof I affix my signature in 70 presence of two witnesses.

JAMES CROSSLEY.

Witnesses:

JOHN G. WILSON,
JOHN HUXE.
